INVENTOR

Benjamin F. Adams

UNITED STATES PATENT OFFICE.

BENJAMIN F. ADAMS, OF BROOKLYN, NEW YORK.

DESIGN FOR A BONBONNIÈRE.

SPECIFICATION forming part of Design No. 16,085, dated May 12, 1885.

Application filed January 26, 1885. Term of patent 3½ years.

To all whom it may concern:

Be it known that I, BENJAMIN F. ADAMS, a citizen of the United States, and a resident of Brooklyn, in the county of Kings and State 5 of New York, have invented and produced a Design for a Bonbonnière, of which the following is a specification.

My invention relates to a casing or receptacle which is known as a "bonbonnière," 10 and which is more particularly intended for holding confectionery.

My design consists in a casing or receptacle having the form and appearance of a miniature barrel.

15 My design consists of a vessel for containing candy, and it is constructed as shown in the accompanying photograph—that is to say, it is of an elongated approximate cylindrical form, bulging at and near its center, and having flush or unbroken ends, and ornamented with encircling bands or beads.

In the accompanying photograph, A represents an elongated hollow vessel of approxi-

mate cylindrical form, bulging outward at and near its center, and having both of its ends 25 smooth or unbroken. Near each end of the vessel are two peripherical ribs or bands, B B, and between these two pairs or sets of ribs or bands on the bulging portion of the vessel are two similar ribs or bands, D D. 30

What I claim, and desire to secure by Letters Patent, is—

A design for a bonbonnière, consisting of a vessel having an elongated approximate cylindrical form, bulging at and near its center, 35 and having flush or unbroken ends, and ornamented with encircling beads or bands, substantially as shown and described.

Signed at New York, in the county of New York and State of New York, this 22d day of 40 January, A. D. 1885.

BENJAMIN F. ADAMS.
